UNITED STATES PATENT OFFICE.

HAROLD L. GRAY, OF CRAWFORDSVILLE, INDIANA.

GRAIN-ELEVATOR.

1,286,999.

Specification of Letters Patent. Patented Dec. 10, 1918.

Application filed July 11, 1918. Serial No. 244,374.

To all whom it may concern:

Be it known that I, HAROLD L. GRAY, a citizen of the United States, residing at Crawfordsville, in the county of Montgomery and State of Indiana, have invented certain new and useful Improvements in Grain-Elevators, of which the following is a specification.

This invention relates to grain elevators and more particularly to automatic shut offs adapted to stop the elevator, thereby to prevent very heavy loads accumulating at the top of the elevator and clogging the conveyers and other mechanisms associated therewith.

One of the objects of the present invention is to provide a simple and practical mechanism of the above general character adapted automatically to shut off the supply of grain to the elevator pit. A further object is to provide a mechanism of the above general character having relatively few parts which may be inexpensively manufactured and installed in elevators now in use.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof, all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, wherein is shown semi-diagrammatically an elevational view of a portion of a grain elevator with such parts of the invention applied thereto as necessary for those skilled in the art to understand the same.

Referring now to the drawing in detail, 1 and 2 denote the opposite legs of an elevator in which is positioned an endless chain 3 adapted to travel about pulleys 4 at the top and bottom for carrying grain or the like from a well or boot 5 upwardly to

a head 6. 7 denotes the intake hopper into which the grain is unloaded from cars or wagons to the boot 5. The head 6 is provided with an outlet 8 for distributing the grain to bins or other receptacles, as desired. These parts are all of well known construction and require no detailed explanation either as to their use or operation.

Adjacent the outlet 8 there is provided an overflow 10 with a downwardly extending pipe 11 terminating in a vertically disposed movable pipe 12 telescoping at its upper end with the pipe 11 on the outer side, and a second pipe 13 on the inner side. This pipe 13 communicates with the receiving hopper 7.

The pipe 12 is supported by means of brackets 14 from a rod 15, the upper end of which rod is connected by means of rope 75 or chain 16 with a counterweight 17. The lower end of this rod is provided with a valve or gate 18 adapted to coact with certain guides acting as a valve seat, whereby as the gate is raised and lowered the supply 80 of grain from either the overflow pipe 13 or hopper 17 to the boot 5 of the elevator will be controlled.

Within the telescopic pipe 12 is an adjustable gate or baffle 20 of any desired 85 type adapted to nearly close the passage therethrough yet provide a small opening 21 through which the grain may slowly pass or leak out when this pipe 12 has been filled from the overflow.

The operation of this device is substantially as follows: When the spout at the head of the elevator has filled up to the overflow pipe 10 the grain begins to fall through this opening and run into the telescopic pipe 95 12. When this pipe fills to a certain degree by reason of the gate or baffle 12, the weight 17 is counteracted which causes the valve rod 15 to move downwardly and shut off the feed of grain into the boot 5 by reason 100 of the gate 18, thus shutting off the feed to the upwardly moving conveyer 3, and thereby prevent a very heavy load in the head 6 with consequent clogging of the discharge mechanism and associated parts contained therein. After the material in the telescopic pipe 12 begins to run out through the small hole 21 provided by the valve, the weight of the member 17 will exceed that of the pipe 12 and its load and open the valve 18, thereby 105 permitting the mechanism to continue its work. Suitable automatic stop mechanism 110

for the conveyer may be installed to co-operate with this gate, if so desired, as indicated at 19.

- It is thus seen that the present invention 5 provides a simple and practical shut off mechanism for grain elevators which is largely automatic in its operation and designed to overcome the objections to mechanisms of this general type heretofore used. 10 The entire apparatus is of simple and practical construction and may be installed at a minimum expense.

I realize that considerable variation is 15 possible in the details of construction and arrangement of parts without departing from the spirit of my invention, and I therefore do not intend to limit myself to the specific form shown and described.

I claim:

- 20 1. In a mechanism of the character described, in combination, an elevator having a conveyer therein, and a discharge outlet from the head, a receiving hopper adjacent the boot, an overflow pipe leading from a point adjacent the discharge to the receiving hopper, a gate interposed between said overflow pipe and the boot, and means adapted to close said gate and stop the conveyer when overflow takes place.
- 25 2. In a mechanism of the character described, in combination, an elevator having a conveyer therein, a discharge pipe leading from the boot, a receiving hopper adjacent the boot, a separate overflow pipe leading directly from the head to a point adjacent the receiving hopper, a gate interposed between the end of said overflow pipe and the boot, and means adapted to close said gate when overflow takes place, said means including 30 a telescopic member located in and forming a part of said pipe and connected with said

gate, counter-weight means holding said telescopic portion in normal upward position, and a baffle located in said telescopic pipe adapted to retard excessive overflow 45 whereby when the weight of said telescopic member and the overflow contained therein exceeds the weight of the counterweight means said gate will close.

3. In a mechanism of the character described, in combination, an elevator having a conveyer therein, a discharge pipe, a receiving hopper adjacent the boot, an overflow pipe having a movable portion leading from the head to a point adjacent the boot, 50 a gate at the lower end of said pipe, a rod connected with said gate at one end and the movable portion of said overflow pipe at the opposite end, a counterweight for said pipe and gate, and retarding means in said pipe whereby an excessive overflow will partially fill said movable pipe thereby to exceed the counterweight and cause a lowering of the movable portion of the overflow pipe and consequent closing of the gate. 55

4. In a mechanism of the character described, in combination, an elevator having a conveyer, a discharge pipe leading from the boot, a receiving hopper adjacent the boot, a separate overflow pipe leading directly from the head to a point adjacent the receiving hopper, a gate interposed between the end of said overflow pipe and the boot, and means adapted to close said gate and stop the conveyer when a material amount 70 of overflow takes place. 75

In testimony whereof I affix my signature in the presence of two witnesses.

HAROLD L. GRAY.
